CLAIM

We claim the ornamental design for a digital signage integrated display stand, as shown and described.

DESCRIPTION

FIG. 1 is a perspective view of a digital signage integrated display stand showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing a state in which product information is displayed on the screen; and,

FIG. 9 is a perspective view showing a state of use thereof. The broken lines in FIGS. 1, 2, 6, 8 and 9 depict portions of the digital signage integrated display stand that form no part of the claimed design. The broken lines in FIG. 8 showing product information and in FIG. 9 showing a second display stand are for the purpose of illustrating an environment of use and form no part of the claimed design.
